UNITED STATES PATENT OFFICE.

EUGENE BUSWELL, OF WATERLOO, IOWA.

OPERATING MECHANISM FOR WASHING-MACHINES.

1,121,610.

Specification of Letters Patent.

Patented Dec. 22, 1914.

Application filed October 27, 1913. Serial No. 797,585.

To all whom it may concern:

Be it known that I, EUGENE BUSWELL, a citizen of the United States of America, and a resident of Waterloo, Blackhawk county, Iowa, have invented certain new and useful Improvements in Operating Mechanism for Washing-Machines, of which the following is a specification.

My invention relates to improvements in washing-machines, and the object of my improvement is to furnish a simple and a convenient actuating mechanism for the rocker-body within the tub, said means comprising hand-levers which may be alternately manually actuated by the operator to rock said body.

This object I have accomplished by the means which are hereinafter described, and claimed, and which are illustrated in the accompanying drawings, in which:

Figure 1 is a side elevation of the washing-machine equipped with my improved actuating-means. Fig. 2 is an upper plan view of the tub of said machine, and the cable connections only for the hand-levers, the latter not being shown. Fig. 3 is an elevation of the bracket casting, its bearings, and the hand-levers pivotally connected thereto, the upper parts of said levers being broken away.

Similar numerals of reference denote corresponding parts throughout the several views.

The washing-machine tub 6 has a hinged top cover 5, with means for securing same in a closed position, and said cover having a central opening, through which extends a central vertical shaft, having a clothes-steering rocker-body secured to its lower end within the tub, the upper end of said shaft having mounted thereon, a pulley 1 provided with two horizontal cable-grooves to seat the two short cables 3 and 4, respectively. Said pulley has a housing 2 about it, mounted upon the said cover 5, the housing having openings to permit of the passage of said cables 3 and 4, whose ends are secured to said pulley to work and be seated in its said groove, while the outer ends of the cables are respectively provided with the blocks 8 and 7, said blocks having integral pintles 10, and 9, respectively, which are rotatably secured in bearing studs on the handle-bars 14 and 13, respectively.

Set-screws 12 and 11, respectively, secure 55 said blocks 8 and 7 adjustably upon said cables 3 and 4.

The numeral 20 denotes a casting plate, which is secured to the outside of the tub 6, and has a vertical rib and also a bracket 15 60 both provided with bearing openings. The lower end of the hand-lever 13 is pivoted upon a pintle 19 connected across between said rib and the bracket 15 at their lower ends, and said lever has a slot 18 situated 65 a short distance about said pintle and adapted to slidably receive a pin 17 projected thereinto from the lower extremity of the hand-lever 14, the last-mentioned lever being fulcrumed on a pintle 16, supported in the bracket 15.

The hand-levers 13 and 14 are grasped in the hands of the operator for alternate oscillation, which causes the short cables 4 and 3 respectively to rock said pulley 1, its vertical shaft and the attached rocker-body in alternate directions. The manner in which the lower end of the lever 14 is pivoted, by means of the pin 17 in the slot 18 of the outer lever 13, has the effect of doing away 80 with the abruptness of the change of movement in the rocking operation, since one lever thus retains the other at the end of its stroke, and in that way the strokes are equalized in length, with a consequent freedom from uneven or jerking action. This permits a smooth and even reversal of action, and equalizes the manual draft. In case of any slackness in the cables, the same may be tightened up by adjusting the set- 85 screws 11 and 12, respectively.

Having described my invention, what I claim as new, and desire to secure by Letters Patent, is:

1. In a washing-machine, a rock-shaft 95 mounted therein, bearings, hand-levers fulcrumed in said bearings, a slidable connection between said levers, limiting their movements to equal oppositely-directed simultaneous oscillations, and operative connections between said levers and said shaft adapted to rock the latter alternately in opposite directions when the hand-levers are oscillated.

2. In a washing-machine, a rock-shaft 105 mounted therein, bearings, hand-levers, one lever having its lower extremity fulcrumed in one bearing and having a slot above said

bearing, the other lever having a pin on its lower extremity slidably seated in said slot and being fulcrumed above said pin in another bearing, and operative connections between said levers and said shaft adapted to cause the latter to be rocked alternately reversely when the hand-levers are oscillated.

Signed at Waterloo, Iowa, this 11th day of Oct. 1913.

EUGENE BUSWELL.
